[57] CLAIM

The ornamental design for a burial casket, as shown and described.

DESCRIPTION

FIG. 1 is a perspective view of a burial casket showing my new design, with the upper part of the two-part cover in the open position and the lower part in the closed position;

FIG. 2 is a top plan view of the casket in closed position;

FIG. 3 is a side elevational view, the appearance being the same on both sides;

FIG. 4 is an end elevational view, the appearance being the same on both sides; and

FIG. 5 is an enlarged, fragmentary, perspective view showing a detail of the casket design.
